APPARATUS FOR REMOVING BOILER IMPURITIES AND FOR PREVENTING BOILER SCALE

Albert Czeczott, Warsaw, Poland

Application July 10, 1930, Serial No. 467,114
In Poland July 13, 1929

4 Claims. (Cl. 122—381)

Boiler scale and other deposits and impurities in boilers consist of substances of different characters, which are unequally distributed, and hence such substances require different treatments for their elimination. In order to entirely prevent the formation of such deposits and their prejudicial effect upon the functioning and preservation of boilers, my methods as further indicated must be periodically put in use, and when they are properly applied, the usual washing of boilers can be dispensed with.

In order to obtain a satisfactory result, the following operations must be performed.

1. The thin upper layer of the boiler water must be frequently removed, in small quantities as being the most contaminated and in fact by the most prejudicial substances. This removal takes place while the boiler is in operation, and before the substances composing the scale are allowed to deposit upon the boiler surface after the ebullition has ceased.

2. Another removing operation is necessary for the expulsion of all soft deposits or sludge of a less prejudicial nature, which collect at the bottom of the boiler after it has ceased working, that is, as soon as the energetic circulation of the mass of water has stopped. This removal may even be effected under pressure, but after a longer period of functioning, for instance a day's work.

3. It is quite necessary to proceed with an entire and periodic removal of the water, as this counteracts the continually increased concentration of salts which are dissolved in the whole amount of water in the boiler, and which could not be removed by the preceding operations. The water is changed according to the periods required for the usual washing. This operation is carried out under pressure, but on condition that the water shall be discharged, not by the usual drain cocks positioned at the lower part of the furnace, but by the special cock serving for the removal of small quantities at the top of the boiler, for otherwise, as the clean water supplied at the same time by the injector is colder, it will descend to the bottom of the boiler and will not remain therein, so that the water is not in fact renewed.

When operating upon this plan, and on condition of a regular functioning of the apparatus to be further described which are specially adapted for these operations, the boiler will work without the stops which are required for the ordinary washing, and hence the relief of the pressure will only be necessary for inspection or re-

pairs, which however need only to take place after much longer working periods than in usual practice.

The accompanying drawings show an embodiment of the invention.

Fig. 1 is a lengthwise section of a boiler provided with the apparatus.

Fig. 2 is a corresponding cross section.

Fig. 3 is a horizontal section.

Fig. 4 is a lengthwise section of the drain cock.

Fig. 5 is a corresponding side view.

Figs. 6 and 7 are like views of a water-outlet cock.

The apparatus for evacuating the impurities of the upper layer of water consists of one or more troughs A secured to a float P. An aperture is pierced in the bottom of each trough, and all the apertures are connected, by short tubes, to a somewhat elastic tube C which runs along the boiler and leads to a drain cock V. The float is suspended in the boiler from a vertical hook B, in such manner that the apparatus will rise and fall with the water level in the boiler. One edge of the trough A is lower than the other, so that the trough will always be somewhat submerged in the foamy water of the upper layer of the boiler, and only in the direction of the natural circulation of this layer.

The foamy water collects in the trough A, and when cock V is opened, the collected sediment will be driven out by the steam pressure.

The essential details for the construction of the float are as follows.

A. In order to allow a certain amount of a liquid to enter the float, one or more small apertures are formed in the upper part of the float body, and each opening is connected in a fluid tight manner with a fluid filling pipe.

B. A pressure gauge, connected to the inside of the float, is mounted on the outside of the boiler.

C. The liquid used in the float should have such composition (alcohol, benzine, etc. mixed with water) that its boiling point is below that of water, or less than 100° C.

By this arrangement, after the boiler is put under pressure, the interior of the float will be subject to a pressure which sufficiently exceeds the boiler pressure. This difference of pressure will increase the resistance of the float P body to the outer pressure which tends to crush or damage the float.

Should the said float, having failed to work, be submerged on account of leakage, this will at once be indicated by the said pressure gauge which communicates with the inside of the float,

and herein the gauge shows a pressure which is the same as indicated by the boiler pressure gauge.

An arrangement for supplying the float P with alcohol or other liquid and for indicating the pressure of such liquid is illustrated in the drawings and consists of a pipe P' of flexible form communicating with the interior of the float and extending to the exterior of the boiler. The pipe 5
10 communicates with a gauge P² which is preferably located adjacent the engineer's cab as illustrated in Fig. 1. The pipe P' is in communication with a funnel-like member L by which the supply of alcohol is replenished when required 15 and communication of the funnel is controlled by a valve K.

According to another arrangement for observing the condition of the apparatus, I insert a one millimeter wire X into the tube C, the wire being attached at one end to the trough A and at the other end to a special rod mounted beside the clack valve of the blow-out cock V. Should the tube C break, the wire will also be broken, and the steam pressure now acts upon the rod and 25 drives it out of the cock, thus indicating the damage.

To evacuate the sludge deposited on the bottom of the boiler after its work has been performed, I employ a water-outlet cock or valve 30 M; such cocks of the known construction usually fail to work, as they are obstructed by particles of matter situated below the clack disk, which prevent the tight closing. In my said apparatus, the cock or valve is provided with a cutting blade F, so that when the valve is operated, the said blade will rotate automatically thus 35 cleaning the passage.

Said cutting blade is rotated by a tooth Z forming part of a lever K; which when the lever K is turned, meets and rotates a toothed wheel t mounted on the stem of the valve, and it also actuates—by a spring H mounted on the lever—a toothed device T which prevents all contrary rotation of the stem. At the input end of the valve 45

is a longitudinal recess n in which the coarser particles collect; such are then ground up by the cutting blade and when reduced to a fine state are freely expelled through the opening of the valve, and without preventing it from working tightly on its seat. The water-outlet cocks may be made in one or more pieces which are suitably mounted at the lower part of the boiler.

I claim:

1. An apparatus for removing the deposits contained in the upper layers of water in boilers comprising a drain cock, a float, a trough supported by said float and an elastic tube between said trough and said cock, means for introducing a quantity of liquid into said floats, adapted, 15 when heated, to produce in the float a pressure exceeding the boiler pressure.

2. An apparatus as claimed in claim 1 characterized by the provision of means for indicating rupture of said elastic tube, said indicating means including a wire connected at one end with said floating trough, said drain cock including 20 a stem and the opposite end of said wire being connected with said stem whereby in the case of rupture of the tube, said wire is also broken thereby releasing the stem and indicating the damage.

3. An apparatus as claimed in claim 1 characterized by the provision of means for indicating the condition of the floating trough, said 25 indicating means including a pressure gauge positioned externally of the boiler and connected with said means for introducing a liquid into said float.

4. Apparatus as claimed in claim 1 having a 30 floating scum collector with the front edge directed towards the furnace end of the boiler submerged several millimeters below the superficial layer of water and with its other edges above said layer, said collector being adapted to accumulate the scum by the movement of said water owing to natural circulation in the boiler and intercepting as possible all width of this current.
